(No Model.)

R. S. RUST.
HOG NOSE CUTTER.

No. 594,809.

Patented Nov. 30, 1897.

UNITED STATES PATENT OFFICE.

ROBERT SINGLETON RUST, OF FRONT ROYAL, VIRGINIA, ASSIGNOR TO
THOMAS BOLLING ROBERTSON, OF DELAPLANE, VIRGINIA.

HOG-NOSE CUTTER.

SPECIFICATION forming part of Letters Patent No. 594,809, dated November 30, 1897.

Application filed August 4, 1897. Serial No. 647,080. (No model.)

To all whom it may concern:

Be it known that I, ROBERT SINGLETON RUST, a citizen of the United States, residing at Front Royal, in the county of Warren and 5 State of Virginia, have invented certain new and useful Improvements in Hog-Nose Cutters; and I do hereby declare the following to be a full, clear, and exact description of the invention, such as will enable others skilled 10 in the art to which it appertains to make and use the same.

This invention relates to the care of live stock.

The object is to produce a simple and effective implement adapted for punching or cutting out a piece of flesh from the nose of swine, whereby to prevent them from rooting.

With this object in view the invention consists in the implement for cutting the cartilage or rooter of the nose of swine, as will be 20 hereinafter fully described and claimed.

In the accompanying drawings, forming a part of this specification, and in which like letters of reference indicate corresponding 25 parts, I have illustrated one form of embodiment of my invention, although it is to be understood that other forms of embodiment thereof may be employed without departing from the spirit of the same, and in these drawings—

Figure 1 is a view in perspective of the implement as it appears when ready for use. Fig. 2 is a view in front elevation, showing 35 simply the jaws carrying the punch and the bed against which the punch contacts. Fig. 3 is a view in plan of a portion of the punch-carrying jaw, looking in the direction of the arrow in Fig. 1, showing particularly the recess in which the punch is held in place. 40 Fig. 4 is a detail view in perspective of the punch removed from the implement; and Fig. 5 is a view in transverse section taken on the line 5 5, Fig. 4, showing particularly the form of the cutter or punch. Fig. 6 is a sectional view taken on the line 6 6, Fig. 3.

Referring to the drawings, A designates the tongs for carrying the operative parts of the implement, which consists of handles a², jaws a³ a⁴, and a rivet or bolt a⁵ for holding 50 the parts assembled. As the tongs may be of any preferred construction, a detailed de-

scription of the form herein shown is deemed unnecessary, as other forms may be employed in lieu of that shown without departing from the spirit of the invention.

The upper jaw a³ is provided on its under side with a recess a⁶, as shown in Fig. 3, this recess extending to the outer end of the jaw and having, in this instance, inclined side walls a⁷, the trend of the incline of both walls 60 being in the same direction, as clearly shown at Fig. 2, to facilitate the insertion of the punch, as will appear later on. The jaw a³ is provided with an approximately semicircular slot a⁸, extending entirely through it, 65 as shown in Figs. 1 and 2, this slot being provided for the purpose of permitting the escape from the implement of the piece of flesh detached from the hog's nose. The jaw a⁴ is provided with a dovetailed recess a⁹, in which 70 is fitted a bed-piece a¹⁰, of lead, leather, or the like, against which the punch will bear in use, the function of which is to prevent dulling of the punch, as will be readily apparent.

The punch B, which forms the essential 75 feature of this invention, is constructed, preferably, of a single piece of metal and comprises a head b and a cutter or punch proper, b². The head is of a shape to fit within the recess a⁶, as shown in Fig. 4, and is provided 80 with an offset b³, adapted to fit within a side recess a¹¹, forming a continuation of the recess a⁶, as shown in Figs. 1 and 3. The outer wall of the jaw in which the recess a¹¹ is formed is countersunk or provided with a depression a¹², as shown in Fig. 3, this depression being engaged by a boss b⁴ on a thumb-nut b⁵, carried by a threaded extension b⁶ on the offset b³. When the punch is in place, the thumb-nut extends parallel with the length 90 of the tongs, as shown in Fig. 1, and will, by means of the boss b⁴ and depression a¹², be prevented from disengagement with the jaw a³; but when the thumb-nut is turned at right angles to the jaw a³ the punch may readily be 95 removed.

As shown in Fig. 4, the disposition of the slot in the head of the cutter is such as to register with the slot a⁸ in the jaw a³, so that the flesh when detached from the hog's nose 100 will be forced through the cutter and out of the slot a⁸ in the upper jaw, thereby prevent-

ing any clogging of the punch, the opening in the punch being approximately wedge-shaped, with its largest end at the discharge, for this purpose.

5 The shape of the cutter is such that when a piece of flesh has been detached it will be impossible for the wound to heal, as the walls thereof are so widely separated that contact between the same will be impossible, so that 10 when a hog's nose has once been operated upon by this implement it will be ever thereafter prevented from rooting.

By reference to Fig. 2 of the drawings it will be seen that the head *b* of the cutter is 15 shaped to fit between the walls *a*⁷ of the recess *a*⁶, so that it will only be necessary to employ a fastening device on one side of the punch to hold it in place, as by the thumb-nut already described. As will be seen by 20 reference to Fig. 2, the right-hand wall of the recess *a*⁶ is straight on its outer side and is then in cut or beveled inward, as indicated by dotted lines in Fig. 3 and in full lines in Fig. 6. The object of this arrangement is to 25 prevent the cutter from working out of the jaw when the device is in use.

In supplying an instrument such as that shown there will be provided a plurality of punches, so that the device will be applicable 30 to operate upon large or small swine, it being only necessary to make the punch portion *b*² smaller or larger, as the case may be, without interfering in any way with the head *b*.

It is to be understood that I do not limit 35 myself to the employment of the threaded extension *b*⁶ to hold the thumb-nut in place on the cutter, as the said nut may be secured by

upsetting the end of the extension, thereby dispensing with the employment of the threads.

Having thus fully described my invention, what I claim as new, and desire to secure by Letters Patent of the United States, is—

1. A pair of tongs comprising, in part, two jaws, one of which is provided with a chamber, having in its rear wall a slot, and in one of its side walls a recess having an external surrounding countersink, in combination with a hollow punch, having a head for engaging the chamber, and with an offset fitting the 45 side recess, and a fastening device adapted to engage the countersink to hold the punch in place, substantially as described.

2. A pair of tongs comprising, in part, two jaws, one of which is provided with a chamber, having in its rear wall a slot, and in one of its side walls a recess having an external surrounding countersink, in combination with a hollow punch, the cutting portion of which is approximately semicircular in cross-section, the punch having a head for engaging the chamber, and with an offset fitting the side recess, and a fastening device adapted to engage the countersink to hold the punch in place, the other jaw being provided 55 with a chamber in which is fitted a yielding bed or contact-face for the cutting edge of the punch, substantially as described.

In testimony whereof I affix my signature in presence of two witnesses.

ROBERT SINGLETON RUST.
